UNITED STATES PATENT OFFICE

155,748

DESIGN FOR AN AIRPLANE HOBBYHORSE

Elmer Szantay, Chicago, Ill., assignor to
Sandee Manufacturing Company

Application March 6, 1948, Serial No. 144,954

Term of patent 14 years

(Cl. D34—15)

To all whom it may concern:

Be it known that I, Elmer Szantay, a citizen of the United States, residing at Chicago, county of Cook and State of Illinois, have invented a new, original, and ornamental Design for an Airplane Hobbyhorse, of which the following is a specification, reference being had to the accompanying drawing forming a part thereof, in which—

Fig. 1 is a top plan view of the airplane hobbyhorse showing my new design;

Fig. 2 is a side elevational view thereof;

Fig. 3 is a front elevational view thereof taken from the line 3—3 of Fig. 2, and

Fig. 4 is a rear elevational view thereof taken from the line 4—4 of Fig. 2.

I claim:

The ornamental design for an airplane hobbyhorse, as shown.

ELMER SZANTAY.
